(57) **ABSTRACT**

An electrical connector comprises an insulating case, a plurality of electrical contacts received in the insulating case, a shutter member mounted on the insulating case and an elastic piece. The insulating case defines a longitudinal direction and comprises a receiving space, a plug fitting section locate beside the receiving space. The shutter member is mounted on the insulating case and comprises a base section movable with respect to the insulating case to close and open the plug fitting section of the insulating case and a mating section extending from the base section into the receiving space to secure with a second mating section. The elastic piece provided in the receiving space and connected with the shutter member to drive the shutter member to elastically close and open the plug fitting section of the insulating case.

20 Claims, 8 Drawing Sheets

FIG 1

FIG. 2

FIG. 3

FIG. 4

FIG. 5

FIG. 6

FIG. 7

FIG. 8

FIG. 9

FIG. 10

FIG. 11

21 to elastically drive the shutter member 21 to close the plug fitting section 411 of the insulating case 4. The wall portion 43 is a board perpendicular to the longitudinal direction. For a width of the neck portion 42 perpendicular to the longitudinal direction is smaller than a corresponding width of the first base portion 41, there is a receiving space 423 defined between the first base portion 41 and the wall portion 43 and adjacent to the neck portion 42. A pair of sliding faces 432 respectively extends downwards from the top of the wall portion 43. Otherwise, step portion 433 is formed on the top of the sliding face 432 and symmetrically arranged about the central line of the shutter member 21. Two shafts 431 are provided on the wall portion 43 to extend into the receiving space 423 so as to mount the shutter member 21.

Referring to FIGS. 6 and 7, the shafts 431 are column-shaped and made of metal. A securing portion 4311 is provided on a surface of one end of the shaft 431 and the securing portion 4311 is a convex rib with guidable side, on the other hand, a rolling portion 4312 is formed on the spare surface of the shaft 431. When the securing portion 4311 is secured into the holes 44, the rolling portion 4312 is exposed out of the receiving space 423.

Then, referring to FIGS. 2 and 4, the pair of first shielding covers 22 is formed and stamped from a metal sheet and configured in an elongated shape. Each of the first shielding covers 22 comprises a plurality of fixing pieces 221 and a plurality of first grounding pieces 222 extending downwards from a lower edge thereof arranging at intervals, a plurality of contact pieces 223 and elastic contact pieces 224 curving upwards from an upper edge thereof at intervals. When the pair of first shielding covers 22 are mounted on the first base portion 41, the fixing pieces 221 are inserted into a space between the first convexities 414 and the second convexities 415 and are secured by the blocks 4141. At the same time, the first grounding pieces 222 are inserted into the slots 4151 and extend downward to connect with the grounding wire of a printed circuit board, also, the contact pieces 223 are fixed into the gap 416 and the forepart of the elastic contact pieces 224 are received into the passage 417.

The shutter member 21 comprises a pair of shutter member halves 21a, 21b of metal. As the halves 21a, 21b are substantially symmetrical, a description will be given of the first half 21a with the understanding that the second half 21b is of substantially similar configuration. The first half 21a comprises a base section. Two separate recesses 214 are provided on opposite ends of the base section of the first half 21a and two smaller recesses 213 are adjacent to the recesses 214. For the two separate recesses 214 are the same, one recess 214 is described. A curving piece 2141 curves downwards from one side to the opening of the recess 214 (FIG. 1). A mating arm 215 is extending downwardly from a distal end 216 which is perpendicular to a surface of the base section of the first half 21a. Further, a locking portion 2151 protrudes from an edge of the mating arm 215 to the curving piece 2141 and a pivot hole 2152 is provided in free end of the mating arm 215. Otherwise, guide pieces 211 extend downwardly from one edge of the base section of the first half 21a. Specially, the opening direction of the recesses 214, 213 is different from the protruding direction of the guide pieces 211. As shown in FIG. 1, when the pivot hole 2152 of the first half 21a is secured on the shaft 431 of the first insulating case 4, the spring 25 is secured with the responding locking portion 2151. Under certain force, the shutter member 21 is able to close and open the first plug fitting section 411 of the receptacle connector 2. When the shutter member 21 is closed, the opening formed by the two

smaller recesses 213 of the shutter member halves 21a, 21b communicates with the through-hole 413, the opening formed by the two recesses 214 of the shutter member halves 21a, 21b communicates with the receiving space 423. 5 Simultaneously, the distal ends 216 abut against the step portions 433 and the guide pieces 211 meet the contact pieces 223 of the first shielding covers 22. As a result, dust and dirt can not enter into the first plug fitting section 411 to contaminate the first electrical contacts 23. On the other 10 hand, while the shutter members 21 open the first plug fitting section 411, the guide pieces 211 are sliding along the contact pieces 223.

Then, referring to FIG. 3, the plug connector 3 consists of a second insulating unitary elongate case 6, a pair of second 15 shielding covers 31 mounted on an outer periphery of the second insulating case 6 and grounding contacts 32. The second insulating case 6 comprise a second base portion 61, a second plug fitting section 62 extending upwardly from the second base portion 61 and a pair of separate guide devices 20 63. A plurality of slots 6111 is located on a pair of ribs 611 extruding from opposite sides of the second base portion 61. The second plug fitting section 62 is provided with a second bottom board 34 mounted thereon and has a groove along the longitudinal direction. The second plug fitting section 62 25 protrudes into the groove accommodating a plurality of second electrical contacts 33 at two sides thereof. The plurality of second electrical contacts 33 extends downwardly through the second base portion 61 and the second bottom board 34 to connect with a printed circuit board. 30 Furthermore, a pair of separate guide tapers 621 extends upwardly from opposite ends of the second plug fitting section 62 to connect with the first plug fitting section 411 of the receptacle connector 2. In addition, the guide devices 63 extended from the second base portion 61 are adjacent to 35 the guide tapers 621 at the same direction of the second plug fitting section 62 and the guide tapers 621. On the other hand, a plurality of second grounding pieces 311 extends downwards from the low edge of the second shielding covers 31 and is inserted into the slots 6111 of ribs 611 of the 40 second base portion 61 so as to connect to the ground.

As shown in FIGS. 3 and 5, each of the guide devices 63 has a pair of guide columns. The guide columns are saddle shape and extend perpendicularly to the direction of the arrow A and arranges symmetrically at a distance. Because 45 the pair of guide columns is the same structure, so one of the guide columns is described. The guide column comprises a peak 632, a slant 631, a long groove 634 and an inner surface 633. The slant 631 is located in flank of the guide column and slopes up to form the peak 632. Furthermore, the long 50 groove 634 extends from the peak 632 to a bottom of the second base portion 61 and a longitudinal securing portion 613 of the second base portion 61 is provided on the free end of the long groove 634 and the width of which is more than that of the long groove 634. Both the peak 632 and the slant 55 631 are located in the long groove 634. When the grounding contact 32 of metal material is fitted on the second base portion 61, the grounding contact 32 is secured in the long groove 634 and a bender 321 is provided at the free end of the grounding contact 32 and is secured in the longitudinal 60 securing portion 613 of the second base portion 61. On the other hand, the inner surface 633 of the guide column matches with the surface of the neck portion 42 of the first insulating case 4.

Referring to FIGS. 8-11, when the plug connector 3 is 65 plugged into the receptacle connector 2, firstly, the peak 623 of the guide device 63 enters into the recess 214 and contacts the curving piece 2141 at the point of B. At the moment,

static electricity of the plug connector 3 and the receptacle connector 2 is released through the grounding contact 32, the curving piece 2141, the guide piece 211 and the contact piece 223 of the first shielding cover 22. However, in this moment the second plug fitting section 62 does not contact with the first plug fitting section 411 and the second electrical contacts 33 also does not contact with the first electrical contacts 23. Secondly, the slant 631 of the guide device 63 slides on the curving piece 2141 to the point of C to drive the mating arm 215 to rotate about the shaft 431 and the spring 25 is elongated at the same time. Meanwhile, the guide piece 211 slides on the contact piece 223 so that the second plug fitting section 62 is entirely connected to the first plug fitting section 411. Especially, when the guide column of the guide device 63 moves to the point of C, the transverse width of the guide column accelerates so as to open the shutter members 21 rapidly. To disconnect the first plug fitting section 411 from the second plug fitting section 62, the receptacle connector 2 is disconnected from the plug connector 3. That is to say, when the plug connector 3 is lifted up from the receptacle connector 2, the guide pins 63 come out of the receiving space 423 and the shutter member 21 is closed to be driven by the spring 25. Especially, the step portions 433 can prevent the shutter sheet 21a from coming into collision with the shutter sheet 21b and resulting in suffering destruction as a result of release of the spring 25. Otherwise, the guide pieces 211 can cushion the collision between the shutter sheets 21a, 21b for sliding on the contact pieces 223.

It is to be understood, however, that even though numerous characteristics and advantages of the present invention have been set forth in the foregoing description, together with details of the structure and function of the invention, the disclosure is illustrative only, and changes may be made in detail, especially in matters of shape, size, and arrangement of parts within the principles of the invention to the full extent indicated by the broad general meaning of the terms in which the appended claims are expressed.

What is claimed is:

1. An electrical connector comprising:
an insulating case defining a longitudinal direction and comprising a receiving space, and a plug fitting section located beside the receiving space along the longitudinal direction;
a plurality of electrical contacts received in the plug fitting section of the insulating case;
a shutter member mounted on the insulating case and comprising a base section movable with respect to the insulating case to close and open the plug fitting section of the insulating case and a mating section extending from the base section into the receiving space to secure with the insulating case; and
an elastic piece provided in the receiving space and connected with the shutter member to elastically drive the shutter member to close the plug fitting section of the insulating case.

2. The elecuical connector according to claim 1, wherein the receiving space is provided with a second mating section engaging with the mating section.

3. The electrical connector according to claim 2, wherein the insulating case comprises a base portion and a wall portion.

4. The electrical connector according to claim 3, wherein the base portion is formed with a neck portion on at least one end thereof and between the base portion and the wall portion, and wherein a width of the neck portion perpendicular to the longitudinal direction is smaller than a corre-

sponding width of the base portion, the elastic piece is provided in the receiving space above the neck portion and the second mating section is in the receiving space adjacent to the neck portion.

5. The electrical connector according to claim 4, wherein the neck portion comprises a concave located inside of the receiving space, the elastic piece is mounted in the concave.

10 6. The electrical connector according to claim 5, wherein the concave is located on the neck portion adjacent to the wall portion, and wherein the second mating portion is provided on the wall portion.

15 7. The electrical connector according to claim 5, wherein the concave is located on the neck portion adjacent to the base portion, and wherein the second mating section is provided on the base portion.

8. The electrical connector according Co claim 3, wherein a top of the wall portion is formed with a step portion, and wherein the shutter member lean against the step portion when the shutter member closes.

20 9. The electrical connector according to claim 2, wherein the shutter member comprises a mating arm extending from the base section into the receiving space and the mating section is provided on the mating arm.

25 10. The electrical connector according to claim 9, wherein the mating section is a pivot hole and the second mating section is a shaft.

11. The electrical connector according to claim 1, wherein the shutter member comprises a pair of lengthwise shutter member halves and each of the lengthwise shutter member halves comprises a locking portion to connect with one end of the elastic piece.

30 12. The electrical connector according to claim 1, wherein a plug connector for mating with the electrical connector comprises a guide device driving the shutter member to open the plug fitting section.

13. The electrical connector according to claim 2. wherein the shutter member is made of metal, and wherein the second mating section is a metallic shaft.

40 14. The electrical connector according to claim 13, wherein the insulating case comprises at least one hole, and wherein the metallic shaft is secured into the hole and extends into the receiving space.

15. The electrical connector according to claim 14, wherein the shaft comprises a securing portion secured into the hole and a rolling portion exposed out of the hole.

45 16. The electrical connector according to claim 15, wherein the securing portion is a convex rib on a surface of the shaft.

17. The electrical connector according to claim 1, further comprising shielding covers mounted on the insulating case.

50 18. The electrical connector according to claim 1, further comprising a bottom board, and wherein the plurality of electrical contacts extends downwards through the bottom board and adjacent to connect with a printed circuit board.

19. An electrical connector assembly comprising:
a first connector including:

first insulative housing defining a mating opening in a vertical direction and a cavity at one lengthwise end thereof;
a plurality of first contacts disposed in the first housing in communication with said mating opening;
a shutter defining a mating arm pivotally secured around an inner wall of the housing facing said cavity, and an elongated ceiling covering said mating opening; and
a second connector including:
a second insulative housing defining a post at one lengthwise end thereof;

a plurality of second contacts disposed in the second housing; wherein when the first connector and the second connector are mated with each other, the post is inserted into the cavity and cooperates with the inner wall to sandwich said mating arm therebetween in a lengthwise direction. 5

20. An electrical connector assembly comprising:
a first connector including;
first insulative housing defining a mating opening in a 10 vertical direction and a cavity at one lengthwise end thereof;
a plurality of first contacts disposed in the first housing in communication with said mating opening;
a shutter defining a mating arm pivotally secured in said 15 cavity, an abutment section adjacent to said mating arm

and around the cavity, and an elongated ceiling relatively far from said mating arm and said abutment section to cover said mating opening; and
a second connector including:
a second insulative housing defining a post at one lengthwise end thereof;
a plurality of second contacts disposed in the second housing; wherein when the fast connector and the second connector are mated with each other, the post is inserted into the cavity and actuates said shutter to open by means of engagement with said abutment section.
